ANATOL GOLLOS, OF CHICAGO, ILLINOIS, ASSIGNOR TO GOLLOS RAILWAY SIGNAL COMPANY OF AMERICA, A CORPORATION OF MAINE.

TRACK SYSTEM FOR CONTROLLING TRAINS.

1,170,483.

Specification of Letters Patent.

Patented Feb. 1, 1916.

Application filed January 22, 1914. Serial No. 813,661.

To all whom it may concern:

Be it known that I, ANATOL GOLLOS, a citizen of the United States, residing at Chicago, in the county of Cook and State of Illinois, have invented certain new and useful Improvements in Track Systems for Controlling Trains, of which the following is a specification.

This invention relates to an electric system or apparatus which is applied to a railway track for the purpose of coöperating with suitable cab systems or train apparatus, for the purpose of stopping trains under certain conditions and controlling the speed of trains under other conditions.

Among the objects of this invention are to provide a system of this character which will permit the operation of trains at full speed over as large a portion of the track as possible, and will provide for suitable caution and danger conditions; to provide a track system which will be as simple as consistent with the necessary operations to be performed, and which will require a minimum amount of wiring; and, to provide means for supplying contact rails with full voltage under certain conditions, reduced voltage under other conditions, and to de-energize such rails under other conditions; and in general to improve such track systems, and provide such additional features and advantages as will be described and pointed out hereinafter.

In the accompanying drawings illustrating my invention, Figure 1 represents the system as applied to a double track railway or one in which the trains all move in the same direction, parts being indicated diagrammatically; Fig. 2 is an elevation of a portion of a contact rail; Fig. 3 is an end view of the same; and, Fig. 4 is a diagrammatical view showing the system as applied to a single track railway, or one in which the trains may move in either direction.

The railway track is divided into blocks A, B, C, D, and E, as indicated in Fig. 1, by providing insulating joints for the rails at the ends of the blocks. A section about three thousand feet long, or sufficiently long to permit the stopping of an ordinary train, is divided off from the entrance end of each block by providing insulating joints. The balance of the block may be of any desired length, but is usually much longer than this

end section. The opposite rails, for instance as indicated at b^2 and b^3 of the short section 55 of the block B, are connected by means of wires b^4 and b^5 with a battery b^6 . The connections from the battery to these rails are preferably made at the exit end of the section, in order to provide for detecting 60 broken rails or connections, as will be hereinafter described. The rails b^2 and b^3 are respectively connected at the entrance end of the block, by means of wires b^7 and b^8 65 with a relay b^9 . The rails b^{10} and b^{11} which constitute the remaining portion of the rails of the block B, are connected at their entrance ends by means of wires b^{12} and b^{13} , to a second relay b^{14} . A contact rail b^{15} is 70 placed about three thousand feet from the exit end of the block, or a sufficient distance so that a train may be stopped between the rail and the end of the block. Another contact rail b^{16} is placed at the exit end of the 75 block. The rails b^{10} and b^{11} are connected by means of wires b^{17} and b^{18} with a battery b^{19} , such connections being preferably made adjacent to the end of the block. The wire b^{18} is preferably carried along the sides of 80 the contact rails b^{15} and b^{16} and connected to the rails, or to the housings which cover such rails, as clearly indicated in Figs. 2 and 3. This wire is insulated from the contact rails, but such arrangement or connection is provided so that if either of these rails becomes dislodged or torn away, the wire will be broken which will open the track circuit and cause a danger condition, 85 as will be presently described.

For convenience in tracing the circuits the duplicate or similar parts in the different blocks are given the same numeral and lettered according to the blocks in which they occur.

The rail a^{11} is connected by means of a wire b^{20} to one terminal of a battery b^{21} , the other terminal of this battery being connected by means of a wire b^{22} with a contact b^{23} of the armature b^{24} of the relay b^{14} . 100 This armature is connected by means of a wire b^{25} with a contact b^{26} of the armature b^{27} of the relay b^9 . This armature is connected by means of a wire b^{28} with the contact rail a^{16} .

The wire b^{22} is connected through a wire b^{29} with a contact b^{30} of the armature b^{31} of the relay b^{14} . The armature b^{31} is connected

by means of a wire b^{32} with a contact b^{33} of the armature b^{34} of the relay b^9 . The armature b^{34} is connected by means of a wire b^{35} with the contact rail a^{15} . The wire b^{22} is also connected through a resistance b^{36} and wire b^{37} with a contact b^{38} of the armature b^{31} , with which the armature engages when the relay b^{14} drops.

If desired, my improved system may be used in connection with the ordinary block signal systems, such signals being ordinarily adapted to indicate "clear", "caution", and "danger". The signal b^{39} at the entrance of the block B, for instance being shown to represent a clear track; the signal c^{39} at the entrance of block C being shown to indicate a caution condition, and the signals d^{39} and e^{39} being shown to indicate danger.

This improved track system is particularly intended to coöperate with a cab system, or apparatus carried by a car or train, having stop devices which will be actuated when a deenergized rail is encountered, and having speed control devices which will be actuated when a partially energized rail, or rail with reduced voltage is encountered. Such an apparatus is shown in my applications filed March 14, 1913, Serial No. 754,186, and May 16, 1913, Serial No. 767,991, and 30 in a third application filed herewith. The particular function of the track system is in general, to provide means for energizing the contact rails under clear conditions; to supply a current of reduced voltage to certain 35 of the contact rails under caution conditions or when a train should be run at relatively slow speed; and to deenergize the rails under danger conditions, or when the train should be stopped. The operation of the 40 system will now be readily understood from Fig. 1, which indicates these three different conditions. The trains move in the direction indicated by the arrow, and the wheels and axles F, F' indicate trains or cars in 45 different positions in the blocks. The position of the apparatus at the beginning of the block B indicates the normal condition for clear track. In such condition the current from the battery b^6 passes through wire b^5 , rail b^3 , wire b^8 , relay b^9 , wire b^7 , rail b^2 and wire b^4 , and back to the battery, thus 50 energizing the relay b^9 and holding its armatures in raised position. The current from the battery b^{19} flows through the wire b^{18} , rail b^{11} , wire b^{13} , relay b^{14} , wire b^{12} , rail b^{10} , wire b^{17} back to the battery, thus 55 energizing the relay b^{14} and holding its armatures in raised position. The contact rail a^{15} is then energized by the battery b^{21} , one terminal of the battery being connected through wires b^{22} and b^{29} , contact b^{30} , relay b^{31} , wire b^{32} , contact b^{33} , armature b^{34} and wire b^{35} . The other terminal of the battery b^{21} is connected through the wire b^{20} 60 with the rail a^{11} , thus forming a portion of

a potential circuit which is completed when the car or locomotive passes the contact rail. The contact rail a^{16} is also energized by the battery 70 21, one terminal of the battery being connected to the rail through the wire b^{22} , contact b^{23} , armature b^{24} , wire b^{25} , contact b^{26} , armature b^{27} and wire b^{28} . This also forms a partial circuit which is completed when the train passes the contact rail a^{16} . When the contact rails are thus fully 75 energized from their corresponding batteries, the current thus supplied will prevent the operation of the stop or control devices on the train, and the train may proceed under full speed. Any condition, or accident, or failure of the system which will deenergize the contact rails will indicate danger, and the train will be stopped when it comes in contact with such a deenergized rail. For instance if the battery b^6 fails, or 80 if the rails or connections from the battery to the relay b^9 are broken, this relay will drop and will open the circuits from the battery b^{21} to the contact rails. A car or train in this section of the block will act 85 to short circuit such battery and deenergize the magnet b^9 as will be seen at the entrance to block E. If the battery b^{19} is short circuited or if any of the rails and connections between this battery and the relay b^{14} become broken such relay will drop. The presence of a car or train in this portion of the block, as indicated at F in block D will 90 short circuit the battery d^6 and the relay will drop as indicated at the beginning of 95 block D. The dropping of the armature b^{24} opens the circuit from the battery b^{21} to the contact rail a^{16} which thus becomes deenergized. The dropping of the armature b^{31} opens the direct circuit from the battery b^{21} 100 to the contact rail a^{15} , but it also closes a circuit from the battery, through a resistance b^{36} (as indicated at the beginning of the block D) so that the rail a^{15} instead of being deenergized, receives a current of 105 reduced voltage from the battery. Such current supplied to the contact rail a^{15} is intended to actuate the speed control mechanism on the train, but will not actuate the 110 stop mechanism.

When a train enters the block as indicated at C and the engineer notes the caution signal c^{39} (provided such block signals are used) he may proceed at full speed until he observes the danger signal d^{39} , when he is 115 supposed to reduce the speed and run under caution as such danger signal indicates the presence of a car or train F in the block D. However, if he does not reduce the speed of the train it will be automatically reduced 120 when the contact shoe comes in engagement with the contact rail c^{15} . Then if the engineer does not stop before the contact shoe comes in engagement with the contact rail c^{16} , the train will be stopped automatically. 125

However, if the train indicated at F should pass out of the block D, before the train reaches the contact rail h^{16} , such rail will then be fully energized and would restore 5 the speed control mechanism to normal condition so that the engineer could proceed under full speed. If the car or train in advance again stopped in the section at the beginning of the block E and the train proceeded toward such a block, it would be stopped automatically when the contact rail h^{15} was encountered, as this rail as well as the contact rail h^{16} would be deenergized. The contact rail h^{15} and the other corresponding contact rails are placed sufficiently far from the end of the block so that a train would have time to be stopped automatically before it reached the end of the block.

While batteries have been specified in the foregoing description, it will be observed that other sources of electricity may be used, if desired, and any suitable amount of current may be provided for operating under various conditions.

25 In the system shown in Fig. 4, which is for a single track railroad or one in which trains may be run in either direction, the track is arranged in blocks, and means are provided for fully protecting the train from 30 both the front and rear, so that it is practically impossible for two trains to unintentionally enter the same block. Each of these blocks is again divided into end sections and a division is made at approximately the center of the block. Taking the block H for instance, a section formed by the rails h^1 and h^2 is approximately three thousand feet long, and the section formed by the rails h^3 and h^4 completes the distance to the center 35 of the block. Taking the block H for instance, a section formed by the rails h^1 and h^2 is approximately three thousand feet long, and the section formed by the rails h^3 and h^4 completes the distance to the center 40 of the block, and the sections formed by the rails h^5 , h^6 , h^7 and h^8 complete the other half of the block. A battery h^9 is connected by means of a wire h^{10} with the rail h^1 , which in turn is connected by means of a wire h^{11} to a 45 relay h^{12} , the return from the relay being through a wire h^{13} , rail h^2 , and wire h^{14} . The battery or source of electricity h^{15} is connected by means of a wire h^{16} with the rail h^3 which is in turn connected by means of a wire h^{17} 50 with a relay h^{18} , the return from the relay being through wire h^{19} , rail h^4 and wire h^{20} back to battery. The battery h^{21} is connected by means of a wire h^{22} with the rail h^5 , which is in turn connected by means of a wire h^{23} 55 with a relay h^{24} at the exit end of the block. The return from this relay is through wire h^{25} and rail h^6 and wire h^{26} back to battery. The battery h^{27} is connected by means of a wire h^{28} with the rail h^7 which is connected by means of a wire h^{29} 60 with a relay h^{30} , the return from the relay being through wire h^{31} , rail h^8 and wire h^{32} back to battery. The contact rail h^{33} is connected by means of a wire h^{34} with a contact g^{35} of an armature g^{36} of the relay g^{30} . The armature g^{36} is connected by means of a wire g^{37} with a contact g^{38} of an armature g^{39} of the relay g^{24} . The armature g^{39} is connected by means of a wire g^{40} with a contact g^{41} of an armature g^{42} , of a relay g^{43} . The 70 armature g^{42} is connected by means of a wire g^{44} to one terminal of a battery g^{45} . The other terminal of the battery is connected by means of wires g^{46} and h^{13} with the rail h^2 . The contact rail h^{47} is connected by means of a wire h^{48} to an armature h^{49} of the relay h^{12} . The contact h^{50} is connected by means of a wire h^{51} with a contact g^{52} of an armature g^{53} of the relay g^{30} . The armature g^{53} is connected by means of a wire g^{54} with a contact g^{55} of an armature g^{56} of the relay g^{24} . The armature g^{56} is connected by means of a wire g^{57} with a contact g^{58} of an armature g^{59} of the relay g^{43} . The armature g^{59} is connected by wire g^{60} with one terminal 80 of the battery h^{61} , the other terminal of this battery being connected by means of wires h^{62} , h^{63} and h^{19} to the rail h^4 . The contact rails h^{33} and h^{47} are arranged on one side of the track at one end of the block H, as shown 90 in the drawings, and another pair of contact rails h^{64} and h^{65} are arranged on the opposite side of the track at the other end of the block. This arrangement is carried out throughout the system, the contact rails corresponding with rail h^{33} and h^{47} , being the ones which co-act with the contact shoes of the trains moving from right to left as indicated by the arrow N. The contact rails of the various blocks corresponding with the rails h^{64} and h^{65} co-act with the contact shoes moving from left to right, or in the direction indicated by the arrow O. The contact rail h^{64} is connected by means of a wire h^{66} to an armature h^{67} of the relay h^{30} . The contact h^{68} of this armature is connected by means of a wire h^{69} with a contact h^{70} of an armature h^{71} of the relay h^{12} . The armature h^{71} is connected by means of a wire h^{72} with a contact h^{73} of an armature h^{74} of the relay h^{63} . This armature is connected by wire h^{75} with a contact h^{76} of an armature h^{77} of a relay h^{18} . The armature h^{77} is connected by means of a wire h^{78} with one terminal of the battery h^{45} . The other terminal of battery h^{45} is connected by wires h^{46} , h^{81} and h^{25} to the rail h^6 . The contact rail h^{65} is connected by means of a wire h^{82} with a contact h^{83} of an armature h^{84} of the relay h^{12} . The armature h^{84} is connected by means of a wire h^{85} with a contact h^{86} of an armature h^{87} of the relay h^{18} . The armature h^{87} is connected by means of a wire h^{88} with a contact h^{89} of an armature h^{90} of the relay h^{78} . The armature h^{90} is connected by wire h^{91} with one terminal of a battery h^{61} ; the other terminal of this battery being connected by wires h^{62} and h^{81} with the rail h^8 . It will thus be seen that when all of the relays are raised, each contact rail will be 130

energized from a corresponding battery, the other terminal of the battery being connected with the section of the track adjacent to the respective rails. The relay h^{78} 5 is connected by wire h^{94} with an armature h^{95} of the relay h^{24} . The contact h^{96} of this armature is connected by wire h^{97} with an armature h^{98} of the relay h^{39} . The contact h^{99} of this armature is connected by a wire 10 h^{100} with a contact h^{101} of an armature h^{102} of the relay h^{12} . The armature h^{102} is connected by a wire h^{103} with a contact h^{104} of an armature h^{105} of the relay h^{18} . The armature h^{105} is connected by a wire h^{106} to one 15 terminal of a battery h^{107} , the opposite terminal of this battery being connected to a common return P, which is indicated in the drawings by a heavy line. The relay h^{43} is connected by a wire h^{108} to an armature h^{109} 20 of the relay h^{18} . The contact h^{110} of this armature is connected by a wire h^{111} with an armature h^{112} of the relay h^{12} . The contact h^{113} of this armature is connected by a wire h^{114} with a contact g^{115} of an armature g^{116} 25 of the relay g^{30} . This armature is connected by a wire g^{117} with a contact g^{118} of an armature g^{119} of the relay g^{24} . This armature is connected by a wire g^{120} with one terminal of a battery g^{121} , the opposite terminal of this battery being connected to the common 30 return P.

In order to introduce resistance for the train control circuits, that is for the purpose of supplying the contact rails with reduced voltage, the armature h^{56} (of the relay h^{24}) 35 is connected by a wire h^{122} with an armature h^{123} of the relay h^{43} . The contact h^{124} of this armature is connected with one terminal of a resistance h^{125} , the opposite terminal of this resistance being connected by wire h^{126} 40 to the wire h^{60} . The first terminal of this resistance is also connected by a wire h^{127} with an armature h^{128} of the relay h^{24} . The contact h^{129} of this armature is connected by a 45 wire h^{130} to the wire h^{54} . In a similar manner the armature h^{74} (of the relay h^{18}) is connected by wire h^{131} with an armature h^{132} of the relay h^{78} . The contact h^{133} of this armature is connected to one terminal of the 50 resistance h^{134} , the other terminal of this resistance being connected by a wire h^{135} to the wire h^{79} . The first terminal of the resistance h^{134} is connected by a wire h^{136} to an armature h^{137} of the relay h^{18} . The contact h^{138} of this armature is connected by a 55 wire h^{139} with the wire h^{72} .

The operation of this modified system for single track will be readily understood from the above description of the double track system taken in connection with Fig. 4 and the preceding description of the circuits. When the track is in clear condition and proper current is being supplied by the batteries to the various devices and instruments, all of the relays will be raised and all

of the contact rails will be supplied with normal or full amount of current. Anything which will short circuit or open the circuits of any of the track batteries will cause the corresponding relays to drop, 70 which will affect certain of the contact rails, either by deenergizing them or by causing them to be supplied with reduced voltage. For instance, if a car or train Q is in the position indicated in the block G it will 75 form a connection between the rails g^5 and g^6 and short circuit the battery g^{21} . This will cause the relay g^{24} to drop. The dropping of this relay opens the circuit from the battery g^{45} to the contact rail h^{33} and thus 80 deenergizes the rail. It also opens the direct circuit from the battery h^{61} to the contact rail h^{47} but also closes a circuit from this battery through the resistance g^{125} to the contact rail h^{47} , so that this contact rail receives a reduced voltage. The dropping of the relay g^{24} also opens the circuit from the battery g^{121} to the relay h^{43} and causes 85 this relay to drop. The dropping of the relay h^{43} opens the circuit from the battery h^{45} 90 to the contact rail h^{33} and deenergizes this rail. It also opens the direct circuit from the battery h^{61} to the contact rail h^{47} but simultaneously closes a circuit through the resistance h^{125} so that this rail receives current of 95 a reduced voltage. The dropping of the relay g^{24} also opens the circuit from the battery h^{107} to a relay at the entrance of the block G corresponding to the relay h^{78} . This will 100 open the circuit to the contact rail corresponding to the rail h^{65} , and will close a circuit through a resistance (similar to h^{134}) to a rail corresponding to the contact rail h^{64} . In other words the condition at the entrance to block G will be similar to that 105 shown at the entrance to block K. It will thus be seen that with the train in the position indicated at Q four contact rails will be affected on one side of the track and two rails on the opposite side of the track. When a car or train is in position indicated 110 at R in the block K, the rails h^7 and h^8 will be connected and the battery h^{27} will be short circuited. This will cause the dropping of the relay h^{30} . The dropping of this 115 relay opens the circuit from the battery h^{45} to the contact rail m^{33} and deenergizes such rail. It also opens the circuit from the battery m^{61} to the contact rail m^{47} , so that this contact rail is also deenergized. The dropping of the relay h^{30} also opens the circuit 120 from the battery h^{45} to the contact rail h^{64} so that this rail is deenergized. The dropping of the relay h^{30} also opens the circuit to the relay h^{78} , and the dropping of this relay opens the circuit from the battery h^{45} , 125 to the contact rail h^{64} , but at the same time closes a circuit to such rail through the resistance h^{134} , so that such rail receives current of reduced voltage. The dropping of 130

the relay k^{78} also opens the circuit from the battery k^{61} to the contact rail k^{65} and this rail is deenergized. The dropping of the relay k^{39} also opens a circuit to the relay in the block M corresponding to the relay k^{43} which is shown open. This in turn opens and closes the proper circuits so that the contact rail corresponding with the rail k^{33} will be deenergized, and the rail corresponding with the rail k^{47} will receive reduced voltage.

From the above description it will be seen that when a train is in the position in a block indicated at Q or the corresponding battery g^{21} is short circuited, or its circuit broken, the circuits to four contact rails to the right of the train and the circuits to two contact rails to the left of the train will be affected, some of such rails being deenergized, and the others furnished with reduced voltage. When the car or train is in the position indicated at R, four contact rails to the right and three at the left will be affected. From this it will be seen that a train in any section will be protected against the approach of a train from either direction, as such train would be stopped by its automatic apparatus, before it entered the block. In a similar manner any obstruction placed upon the track which would short circuit a track battery, or any opening of the battery circuit would indicate a danger condition similar to the presence of a train, and this would affect a corresponding number of contact rails to the right and left so as to stop a train before entering such block.

By means of my improved system, and particularly on account of the arrangement provided by the short sections which are insulated at the ends of the blocks, I provide an arrangement whereby trains may be operated at full speed to the fullest extent consistent with safe operation and safe automatic control and stopping action. Where a block is utilized in its entirety for control, as indicated in my former applications, it may be necessary for trains to operate under slow speed throughout the entire length of the block, before it comes to a stop or safety condition. In the present instance, a train after observing a caution signal, may run at full speed for approximately the full length of the block, and if the danger condition has not been removed it will be stopped within a sufficient distance of the end of the block. For instance, if a train were entering the block C shown in Fig. 1, the signal c^{39} would indicate caution, but as the danger represented by the train F was in the next block, the engineer may proceed under full speed until he reaches approximately the end of the block C where he would either be stopped, if the danger condition remained; or would be given a clear track if the dan-

ger condition were removed. This arrangement facilitates using blocks of any desired length and also avoids the necessity of any continuous track wires for a double track system, and only requires a minimum amount of such wires for a single track system.

It will be observed that changes may be made in my improved system in order to provide for different track conditions, as for different kinds of railways without departing from the spirit of this invention, and therefore, I do not wish to limit myself to the exact construction or arrangement shown herein, except as specified in the appended claims, in which—

I claim:

1. A track system for controlling trains comprising a track divided into blocks, and each block having a section at the end thereof insulated from the balance of the block, pairs of contact rails arranged adjacent to the exit end of each section, means for energizing said rails, means including a source of electricity and the rails of the insulated section for deenergizing the contact rails at certain times, and means including a source of electricity, and the track rails of the succeeding block for deenergizing one of said rails and reducing the voltage to the other rail at other times.

2. A system of the character set forth, comprising a railway track divided into blocks with each block divided into relatively long and short sections, the short sections being at the entrance ends of the blocks, with pairs of contact rails arranged adjacent to the track, but at some distance from each other, at the exit ends of the long sections, means for supplying electric current to said contact rails, a source of electricity, a relay and circuit including the rails of the short sections of each block for opening the circuits to said contact rails of the adjacent section, and a relay, a battery and a circuit including the track rails of each succeeding block section for opening the circuit to one of said contact rails, and for opening the circuit to the other rail and closing a circuit thereto and a resistance in said last-named circuit.

3. A system of the character set forth, comprising a track divided into blocks and each block being divided into relatively long and short sections, the short sections being at the entrance ends thereof, a contact rail adjacent to the exit end of the long section of each block, a second contact rail at a predetermined distance from the exit end of each block, a source of electricity for these two contact rails of each block, a resistance to be inserted at times in the circuit from said source of electricity to the last named contact rail, a battery for each short section having its terminal connected with the track rails of such section, a relay for each short

section having its terminals connected with the track rails of such section and receiving current from said battery, the armatures of said relay being included in the circuits from said source of electricity to the contact rails, a second relay having its terminals connected with the track rails at the entrance of the nearest succeeding block, a battery having its terminals connected with the rails of said succeeding block and supplying current to said second named relay, the armatures of said second named relay also being included in the circuit from said source of electricity to the contact rails, and one of said armatures being also arranged to close a circuit at times, from the source of electricity through the resistance to the second named contact rail.

4. A system of the character set forth, comprising a track divided into blocks B and C, each block having a section of predetermined length at the entrance end thereof, which is insulated from the remainder of the block, contact rails b^{15} and b^{16} located 25 a predetermined distance apart adjacent to the exit end of the second section of the block B, a source of electricity c^{21} having one terminal connected with the rails of the second section of the block B, a source of electricity c^6 having its terminals connected with the rails of the entrance section of the block C, a relay c^9 having its terminals connected with the rails of the entrance section of the block C, said relay having two armatures, 30 circuits from said source of electricity c^{21} through said armatures to the rails b^{15} and b^{16} , a source of electricity c^{19} having its terminals connected with the rails of the second section of the block C, a relay c^{14} having its terminals connected with 35 said rails, the armatures of said last named relay being included in the circuits from the source of electricity c^{21} to the contact rails, a resistance c^{36} and a circuit from the battery c^{21} to the contact rail b^{15} 40 which is closed through said resistance when the armatures of the relay c^{14} drop.

5. A track system for automatic railway control, comprising a track divided into blocks by having each of the rails insulated at the ends of the blocks and having the blocks divided into relatively short entrance sections and long exit sections, sources of electricity having their terminals connected 50 with the opposite rails adjacent to the exit ends of the blocks, two contact rails arranged adjacent to the exit ends of each of the blocks, relays having their terminals connected with the rails at the entrance ends of the long sections, sources of electricity having their terminals connected with the opposite rails adjacent to the exit ends of the short sections, relays having their terminals connected with the rails at the entrance ends 55 of the blocks, sources of electricity for ener-

gizing the contact rails, circuits from said last named sources of electricity to the contact rails, and the track rails, each of said circuits being controlled by two relays.

6. In a track system of the character set forth, the combination with a track having both the rails insulated at intervals to form blocks and rails of each block insulated to form relatively short entrance sections and long exit sections, of sources of electricity connected with the different rails of each section, relays also having their terminals connected with the different rails of each section and receiving current from said sources, each of said relays having a plurality of armatures, two contact rails for each block, sources of electricity for energizing said contact rails, and connections and circuits from said sources to each contact rail and the track rails, each of said circuits being controlled by two of said relays.

7. A track system of the character set forth comprising a track divided into blocks, each block being divided into two sections, each section being provided with a relay and battery, said relays and batteries being connected in circuits including the rails of the sections, each block also being provided with two contact rails arranged at predetermined distances apart adjacent to the exit ends of the blocks, a source of electricity for each pair of said contact rails and circuits from said sources of electricity to said contact rails, each of said circuits being controlled by each of the relays of the sections.

8. A system of the character set forth comprising a track divided into blocks, and each block divided into sections, a source of electricity and a relay for each section, the circuit from said source to the relay including the rails of the corresponding section, a contact rail arranged adjacent to the end of each block, a second rail arranged a predetermined distance before the first named rail, sources of electricity for supplying current to said rails, circuits from said sources to each of said rails, the circuits from said sources to each of said rails being controlled by the two relays of the succeeding block.

9. In a system of the character set forth, the combination of a track divided into blocks, and each block divided into two sections, of a track battery and relay for each section, the circuits from each battery to its respective relay including the rails of such section, two contact rails arranged at a predetermined distance apart adjacent to the exit ends of each block, a source of electricity for supplying current to each pair of contact rails, the circuits from said sources to the respective contact rails of one block being controlled by the two relays of the next block, a resistance for one of each pair of contact rails and a circuit including such resistance from the source of electricity

to one of each of said contact rails, which circuit is closed by one of the armatures of one of the relays when such armature drops.

10. In a track system of the character set forth, the combination with a track having both rails insulated at intervals to divide the track into blocks and the rails of each block insulated to divide the blocks into sections, of track batteries, each battery having one terminal connected with one rail of a section, and the other terminal connected with the other rail of the section adjacent to the exit end of the section, a relay for each section, each relay having one terminal connected with one rail, and the other terminal connected with the other rail adjacent to the entrance end of the section, two contact rails adjacent to the exit ends of each block, said rails being placed a sufficient distance apart to permit the stopping of a train within such distance, batteries for supplying electricity to said contact rails, a circuit from one terminal of each battery to the track rails at the exit end of each block, two circuits from the other terminal of each battery to the contact rails at the exit end of the corresponding block, the said last named circuits each including the two armatures of the two relays of the next succeeding block, a resistance for one of the circuits from the last named battery to one of the contact rails of each block, and a connection for putting said resistance in circuit when one of the relays controlling the circuit from said battery to the corresponding contact rail is deenergized.

11. The combination with a railway track divided into blocks and each block divided into sections, the first or entrance section of each block being only of sufficient length to permit the convenient stopping of a train within such length, of a relay and a track battery for each section, two contact rails at a predetermined distance apart for the exit section of each block, a contact rail supply battery for each block, connections by which each contact rail of a block is provided with current from its respective battery, means for controlling the circuit connections between each contact rail and its battery by either of the two relays of the succeeding block, and means for controlling said relays by vehicles passing over the railway track.

12. The combination with a railway track divided into blocks and each block divided into entrances and exit sections, of two contact rails for the exit section of each block, said contact rails being arranged sufficiently far apart to permit the stopping of a train between them, a relay for each section, connections for supplying electric current to each contact rail, and means for controlling said connections so as to cut off the current from any contact rail by the operation of either of the two relays of the succeeding

block, a resistance and means for inserting said resistance in the circuit in one of said contact rails of one block, by the action of one of the relays of the succeeding block.

13. In a single track system of the character set forth, the combination with a track having both rails insulated at intervals to form blocks, and insulated within the blocks to form sections, of a source of electricity for supplying current to the rails of each section, a relay for each section receiving current from the rails of said section, an additional relay at each end of the blocks, a battery for each end of each block for supplying electricity to the additional relays at the opposite ends of the adjacent blocks, circuits from said batteries to said relays, each circuit including the armatures of two of the first mentioned relays in one block and two in the adjacent block, two contact rails arranged at predetermined distances apart on one side of the track at one end of the block and two similar rails on the opposite side of the track at the other end of each block, two batteries for each block for supplying current to said contact rails, each battery being connected with one contact rail in one block and another contact rail on the opposite side of the track in the adjacent block, and also being connected with the section of the track corresponding with said contact rails, circuits from said batteries to said rails including the armatures of a plurality of relays, a resistance for one rail of each of the pairs of rails at each end of the blocks and circuits controlled by the armatures of one or more of said relays for putting said resistance in circuit at times between the contact rail and its respective battery.

14. In a single track system of the character set forth, the combination of a track divided into blocks and each block divided into sections, with two contact rails at a predetermined distance apart on one side of the track at one end of each block and two similar contact rails on the opposite side of the track at the opposite end of each block, track batteries and relays for each section, means for normally energizing the contact rails, means controlled by the track relays for deenergizing such rails at times, and means controlled by said track relays for introducing resistance at times into the circuits leading to the contact rails of each pair at the ends of the blocks farthest from the ends.

15. In a track system of the character set forth, the combination of a track divided into blocks and each block divided into four sections, a track battery for each section having its terminals connected with the track rails of the section adjacent to one end of the section, a relay for each section, each relay being connected with the rails at the opposite end of the section from the battery

and receiving current from the battery, a third relay for each end of the block, batteries for each of said third relays, a circuit from each of said last named batteries 5 to its corresponding relay, said circuit including two of the armatures of the corresponding first named relays in one block and two armatures of corresponding relays in the next adjacent block, two contact rails 10 on one side of the track at the entrance ends of the blocks for trains going in one direction, batteries for supplying current to said contact rails, each battery being connected with a contact rail of a preceding block, 15 said connections being through the armatures of a plurality of said relays; contact rails of the opposite side of the track at the entrance ends of the blocks for trains going in the opposite direction, batteries for supplying current to said contact rails, each battery being connected with a contact rail of the corresponding preceding block, said connections including the armatures of a plurality of the relays; a resistance for the 20 second contact rail from the entrance end of each block and circuits controlled by two of the relays for introducing said resistance into the circuit from the battery to the corresponding contact rail.

16. A single track system of the character set forth, comprising a track divided into blocks and each block divided into four sections comprising two entrance sections at the ends of the blocks, of predetermined 25 length, and two intermediate sections, two contact rails in alignment with each other adjacent to the exit ends of the two sections at the exit end of each block for trains going in one direction and corresponding 30 rails at the exit ends of each block on the opposite side of the track for trains going in the opposite direction, track circuits and

relays for each section, and means controlled by certain of said relays for energizing certain of the contact rails and means also 45 controlled by certain of said relays for supplying current of reduced voltage at times to certain of the contact rails.

17. In a system of the character set forth, the combination of a track divided into 50 blocks, contact rails in alignment with each other at predetermined distances apart adjacent to the exit ends of the blocks for trains going in one direction, and similar rails at the exit ends of the blocks for trains 55 going in the opposite direction, means for normally energizing said contact rails and means governed by track conditions for de-energizing said rails at certain times, and means governed by track conditions for de-energizing certain of said contact rails and supplying other contact rails with reduced voltage at other times.

18. In a track system of the character set forth, the combination with a pair of contact rails arranged at a predetermined distance apart adjacent to one end of a block, 60 of means for energizing said rails, a resistance, and selective devices for introducing said resistance in circuit with one of the 65 rails at predetermined times.

19. In a system of the character set forth, the combination of a track divided into blocks, each block being divided into four sections, contact rails for each of said sections, and means for energizing said contact rails, de-energizing said rails or supplying certain of said rails with reduced voltage, 70 substantially as shown and described.

ANATOL GOLLOS.
